UPPER GARMENT

Fredric Seelye, Los Angeles, Calif., assignor, by
mesne assignments, to Hollywood Rogue
Sportswear Corp., Los Angeles, Calif., a corpora-
tion of California

Application January 22, 1946, Serial No. 642,705

1 Claim. (Cl. 2—115)

1

This invention relates to a garment, such as a shirt, or coat.

It is one of the objects of this invention to provide a garment of this character, that is simple to manufacture, and that presents a pleasing appearance.

Shirts utilized either as dress shirts or sport shirts often employ a shoulder yoke requiring a seam at the shoulder. It is another object of this invention to obviate the necessity of such a seam.

This invention possesses many other advantages, and has other objects which may be made more clearly apparent from a consideration of one embodiment of the invention. For this purpose there is shown a form in the drawings accompanying and forming part of the present specification. The form will now be described in detail illustrating the general principles of the invention; but it is to be understood that this detailed description is not to be taken in a limiting sense, since the scope of this invention is best defined by the appended claim.

Referring to the drawings:

Figure 1 is a rear view of a garment embodying the invention;

Fig. 2 is a front view thereof;

Fig. 3 is a plan view of a piece of material formed to provide back and sleeves of the garment; and

Fig. 4 is a plan view of a piece of material formed to provide half of the front portion of the garment.

The shirt or jacket includes the back portion 1. As shown most clearly in Fig. 3, the material for this back portion may be cloth or leather, or any other suitable fabric.

As shown most clearly in Fig. 3, the sleeve forming portions 2 and 3 are integral with the back portion 1. These sleeve forming portions are adapted to be folded respectively to form the sleeves 4 and 5. For this purpose the longitudinal edges 6, 7, 8, and 9 are joined as by a seam to form the lower side of the sleeve. An appropriate cuff, such as 10, may be provided at the end of each sleeve.

The sleeve forming portions 2 and 3 extend to the neck region 11 at the top of the back member 1, thereby forming the shoulders 12 and 13.

In order to complete the garment, two front forming portions 14 and 15 are provided. These portions may be attached, as by sewing, to the

2

corresponding edges of the back forming portion 1. They are also attached, as by sewing, to the corresponding edges 16 and 17 of the sleeve forming portions 2 and 3 that extend toward the front of the garment. An appropriate collar 18 is attached to the neck portion. The front portions 14 and 15 may overlap and may be provided with appropriate detachable fastening devices, such as the buttons 19.

10 The shoulder portions adjacent the neck opening are formed by folding the edges 16, 17 toward the front of the garment. These edges are continued toward the armpit regions by the aid of the edges 16', 17' that curve downwardly. A 15 seam along these edges 16 and 16' extends from the neck opening to the armpit region. This seam progresses upwardly from the armpit and thence substantially parallel to the shoulder line entirely to the neck opening a similar seam along edges 17, 17' is formed at the right-hand side of the garment.

A decorative frame for the front of the garment is formed by the lines 16, 17 of the seam between each of the front portions 14 or 15 and the shoulders.

25 The inventor claims:

In a garment made from woven fabric: a back; sleeve and shoulder portions integral with the back, said sleeve forming portions and the back defining a part of the neck opening, the longitudinal edges of the sleeve portions being joined at the lower side of the sleeve, the shoulder portions extending over the shoulder line and substantially parallel therewith; and front forming

30 members joined to the back member at the sides 35 of the front and back members, each of the front members being joined to the corresponding sleeve and shoulder portions by a seam from the armpit region, said seam extending upwardly from the armpit region, and then substantially parallel to the shoulder line entirely to the neck opening.

FREDRIC SEELYE.
